UNITED STATES PATENT OFFICE.

JACOB J. WAHLE, OF MINDEN, NEVADA.

SCRAPER.

1,235,617.

Specification of Letters Patent. Patented Aug. 7, 1917.

Application filed February 24, 1917. Serial No. 150,806.

To all whom it may concern:

Be it known that I, JACOB J. WAHLE, a citizen of the United States, residing at Minden, in the county of Douglas and State 5 of Nevada, have invented certain new and useful Improvements in Scrapers, of which the following is a specification.

The present invention relates to scoops or scrapers, and the object is to provide a 10 structure that will lighten the draft upon the same, while not interfering with the ordinary filling, transporting and dumping action, the improvements being simple in character and readily applicable to well 15 known types of devices of this character.

In the accompanying drawings there is disclosed a preferred embodiment of the invention, wherein—

Figure 1 is a perspective view of a scoop 20 or scraper, showing the improvements applied thereto,

Fig. 2 is a longitudinal sectional view on the line 2—2 of Fig. 1,

Fig. 3 is a detail vertical sectional view 25 on the line 3—3 of Fig. 1.

Fig. 4 is a view partially in elevation and partially in section of one of the supporting wheels and its axle, together with the hub caps, one of the latter being removed.

Fig. 5 is a detail sectional view on the line 5—5 of Fig. 2.

Similar reference numerals designate corresponding parts in all the figures of the drawings.

In the embodiment illustrated, the scoop or scraper is of well known form, being preferably constructed of sheet metal, having a bottom 6, end walls 7, and a rear wall 8, the connection between the end walls 7 and bottom 6 being preferably reinforced by angle bars 9. A draft bar of well known form is shown at 10, and has a link connection 11 with the end walls. The scraper or scoop body is furthermore provided with suitable dumping runners 12 secured to the end walls 7 and connected by a cross bar 13. A handle bar 14 is attached to the rear wall 8. So far as thus described, no claim is made to the structure *per se*.

In the present embodiment, the end portions of the bottom 6 are provided with upstanding pockets 15, which may be formed by upsetting the bottom or by cutting out said bottom and attaching suitably formed 55 plates thereto. The outer walls of these

pockets 15 are formed by the end walls 7, as will be evident by reference to Fig. 2, said end walls having inturned flanges 16 upon which the reinforcing angle bars 9 rest. The bottom is furthermore provided at the 60 inner sides of the pockets with upset portions 17 forming sockets.

Extending across the lower open sides of the pockets are axles 18, each axle having an outer terminal eye 19 through which a 65 vertical bolt 20 passes, said bolt passing through the inturned flange 16 of the end walls 7 and the reinforcing bar 9, thus securing the outer end of the axle to said end wall. The inner end of the axle is seated 70 in the upset portion or socket 17 of the bottom, as shown in Fig. 5, and is held therein by any suitable means, as for instance, a strap 21 extending across said axle and bolted as shown at 22 to the bottom 6. 75 Journaled on these axles are supporting wheels 23, the hubs 24 of said wheels tapering toward both ends. Interposed between the ends of the hubs and the end walls of the pockets 15 are hub caps 25 that preferably overlap the ends of the hubs 24, so as to serve as a guard, and also act as spacing means for maintaining the wheels in proper positions in the pockets. The upper portions of these wheels, it will be noted operate in said pockets 15, while the lower portions project below the scraper or scoop. 80

A caster wheel 26 is mounted on the rear wall 18, said caster wheel being journaled in a suitable bracket 27 having an upstanding 90 pintle 28 that is mounted in a keeper 29 fixed to the center of the rear wall 8, and permitting the bracket to have a turning or castering action, as will be readily understood. 95

It will be evident that with this wheel mounting the scraper or scoop will more readily move, and thus eliminate the draft or drag upon the team. At the same time, it does not add materially to the weight or cost 100 of the apparatus, nor does it interfere with the usual loading, transporting and dumping action.

From the foregoing, it is thought that the construction, operation and many advantages of the herein described invention will be apparent to those skilled in the art, without further description, and it will be understood that various changes in the size, shape, proportion, and minor details of con- 105 110

struction may be resorted to without departing from the spirit or sacrificing any of the advantages of the invention.

Having thus fully described my invention, what I claim as new, and desire to secure by Letters Patent, is:—

In apparatus of the character set forth, the combination with a scoop body having a bottom, end walls, a back and upstanding pockets in the bottom, the outer sides of said pockets being formed by said end walls, and the bottom having upstanding portions at the inner sides of the pockets, of axles extending across the pockets, said axles hav-

ing outer terminal eyes lying below the end walls and having their inner ends seated and secured in the upstanding portions of the bottoms, fasteners for the axles engaged in the eyes of said axles and engaging the end walls, and wheels journaled on the axles and having their upper portions in the pockets, said wheels projecting below the bottom.

In testimony whereof, I affix my signature in the presence of two witnesses.

JACOB J. WAHLE.

Witnesses:

J. E. DRENDEL,
L. A. McINNIS.
